BUCKLE

Maximilian C. Becker, East Orange, N. J.

Application December 28, 1948, Serial No. 67,710

3 Claims. (Cl. 24—200)

1

This invention relates to novel articles of manufacture. In one of its more specific aspects the invention is directed to novel buckles and also to articles of manufacture having at least one of said novel buckles as a component part thereof. The novel buckles of this invention may be made in one piece units and are of simple and rugged construction.

Fig. 1 is a top plan view of an example of a buckle embodying this invention.

Fig. 2 is an end view of the novel buckle shown in Fig. 1.

Fig. 3 is a perspective view of another example of a buckle embodying this invention.

Fig. 4 is an end view of the novel buckle shown in Fig. 3.

Fig. 5 is a top plan view of a tire chain having novel buckles coupled therewith.

Fig. 6 is a cross-sectional view illustrative of the first and second steps in the method of coupling with a tire and wheel the combination shown in Fig. 5.

Fig. 7 is a cross-sectional view illustrating the next step of coupling.

Fig. 8 is a cross-sectional view of the completed coupling.

Fig. 9 is a perspective view of another modification of the buckle shown in Fig. 1.

Fig. 10 is a diagrammatic view in perspective of a belt embodying the invention.

As shown in Figs. 1 and 2, one of the embodiments of my novel buckles comprises a body 10 composed of any desirable material, such as fabric, leather, metal, wood, plastic, laminated paper or cardboard, which is fairly rigid. Among some of the plastics which may be employed are the phenol-aldehyde, vinyl ester polymers and copolymers, methyl methacrylate etc. resins. The body 10 may be of any desirable shape or configuration and as shown in Figs. 1 and 2, is in the form of a rectangular flat plate. The body 10 has a pair of transverse slots 11 and 12 which are approximately parallel to each other, of the same general width and length and extending through one of the longitudinal edges of body 10. These elongated slots 11 and 12 define an elongated finger 13 at the approximate center of body 10. The body 10 has also a pair of elongated openings 14 and 15 which are approximately parallel to each other, and measuring in length and width about the same as the slots 11 and 12. These openings 14 and 15 are parallel to the slots 11 and 12 and are centrally located well within the longitudinal edges of the body 10. Integral with the body 10 or in any other manner secured thereto are a pair of ribs 16 and 17 located at the outside edges of the slots 11 and 12, with that portion of each of said ribs near the open end of said slots being bevelled or inclined at 18.

If desired, a pair of spaced circular openings or another transverse opening (neither shown)

2

may be provided in either or both ends of the body 10 for anchoring or attaching permanently if desired, one end of a band or belt thereto. Alternatively the endwise dimensions of the openings 14 and 15 may be set so that either of them may serve as an opening through which one end of a band or belt may be anchored and still allow a sufficient widthwise opening therethrough for the demountable locking operation hereinafter described.

In use, a band or the like may have one end thereof anchored or coupled with the body 10 in the manner hereinbefore described. Then the buckle carrying band or belt is wrapped around an object and the free end thereof may be inserted through the opening 14 and a stretch thereof inserted into the slots 11 and 12 and the free end inserted into the opening 15. The bevels or inclines 18 provide a means of ready insertion whereupon the stretch rides upwardly thereon to the main locking portions of the ribs which together with the finger 13 locks the free end against longitudinal movement, and the closed ends of the slots 14 and 15 lock the free end of the band against transverse movement.

In the embodiment shown in Figs. 3 and 4, there is provided a body 20 of any desirable composition. The body 20 comprises a main portion 21, having integral therewith a narrow portion 22 at about 90° to portion 21 and a portion 23 which is integral with portion 22 and off-set with respect to main portion 21. The main portion 21 has a pair of transverse slots 24 and 25 similar to slots 11 and 12 of Fig. 1 except that the outer ends thereof are flared on one side to provide a finger 26 whose outer end 27 is tapered on each side, and said tapered outer end 27 is off-set and located to one side of the front face of main portion 21 in a direction away from or towards the plane of off-set portion 23. Transverse slots 28 and 29 are located in the main portion 21 at that end thereof away from portion 22 and in the portion 23 and are similar to openings 14 and 15 of Fig. 1. These slots 28 and 29 extend through the longitudinal edge of body 20 opposite the longitudinal edge thereof through which slots 24 and 25 extend.

The buckle shown in Figs. 3 and 4 may be coupled with a band or belt and used in the same general manner hereinbefore described in connection with that of Figs. 1 and 2.

The buckle shown in Fig. 9 comprises a body 30 having a main portion 31 and a narrower portion 32 disposed at about right angles to portion 31. The main portion 31 has a pair of slots 33 and 34 therein similar to slots 11 and 12 of Fig. 1 and defining a finger 35, and an opening 36, similar to opening 15, and the minor portion 32 has an opening 37 similar to opening 14. Centrally disposed along the longitudinal axis of the finger 35 is a rib 39 similar to ribs 16 and 17 of Fig. 1.

The adjacent ends of the major and minor portions 31 and 32 have openings 38 for accommodating coupling rings or links of a chain.

It is to be understood that in the embodiment shown in Figs. 1 and 2 but a single rib 17 may be used and located either adjacent a longitudinal edge of one of the slots 11 or 12 or on the central longitudinal axis of finger 13; and that slots similar to slots 28 and 29 may be used instead of openings 14 and 15. Such modifications of the closed openings in Figs. 9 and 10 are also within the scope of this invention.

An embodiment of the combination which may be provided with the novel buckles of this invention is illustrated in Fig. 5. As shown there is a pair of chains 50 and 51. End links of chains 50 and 51 are connected to a buckle 53 of the type shown in Fig. 9 and to a buckle 54 of the type shown in Fig. 1.

The novel combination shown in Fig. 5 may be easily and readily combined with a wheel of an automobile. As shown in Figs. 6-8 there is an illustrative embodiment of said wheel which comprises the wheel per se which is of the disc type and has opening 56 therethrough. Mounted on the rim 57 is the tire 58 and tube 59 combination. The first step which may be employed in combining the so-called emergency chain shown in Fig. 5 with the wheel is to insert one end 60 of a flexible belt 61 through the opening 56. This insertion takes place by standing on the outside of the wheel and inserting the end 60 in the direction of the arrow as shown in Fig. 6 towards the inside of the wheel. Then after a portion of the strap 61 is threaded through the opening 56 in the manner described, the end 60 is grasped by the hand and then is pulled over and around the tire 59 to locate the free end 60 on the outside of the wheel. The strap or belt 61, which I prefer to employ, is of a thickness corresponding to the width of the slots and openings of the buckles 53 and 54. Then the end 60 is coupled with the buckle 54 in the manner heretofore described and the parts are disposed in the relative positions shown in Fig. 6. After this coupling operation the other end of the strap 61 is grasped by the hand and is pulled towards the outside of the wheel to locate the parts in the relative positions shown in Fig. 7. Then this free end of the strap 61 is threaded through the slot 36 and is tightly drawn. A stretch thereof then is inserted in the slots 33 and 34 with a portion thereof bearing against the rib 39 and the outer end of the strap is extended through slot 37. With this arrangement that portion of the strap 61 extending through the slots 33 and 34 and bearing against the rib 39 is snubbed or anchored against longitudinal movement and any force acting longitudinally on the combination will tend to more firmly snub and lock the strap to the buckles 53 and 54, while the closed ends of the slots and the opposite ends of the openings co-act to lock the straps to the buckles against transverse movement.

Still another combination which may be provided with the novel buckles of this invention is illustrated in Fig. 10. As shown there is a body or trouser belt consisting of an elongated strap or band 70, one end 71 of which may be narrowed and the other end of which may have one of the buckles of this invention coupled therewith in any convenient manner. The belt-buckle combination may be a single unitary homogeneous element composed of appropriate plastic material, with the buckle 73 being off-set with re-

spect to the belt proper and of the type shown in Fig. 1. One of the materials which is preferably employed may be any of the polymeric or copolymeric vinyl esters or polymethyl methacrylate, appropriately compounded and cured or seasoned so that the combination may have the desired transverse rigidity characteristics. The entire combination may be compression molded and cured, or extruded and cut and cured or seasoned to provide the combination shown in Fig. 10.

While the various openings such as 14 and 15 of Fig. 1, 28 and 29 of Fig. 3 and 36 and 37 of Fig. 9, as well as those shown in the combinations illustrated in Figs. 5 and 10 are all within the outer longitudinal edges of the buckles, these openings may all be in the form of slots extending through that edge of the buckle opposite the edge through which the finger-defining slots extend.

I claim:

1. A buckle comprising a member having a pair of spaced slots extending through one of the edges thereof, a finger between said slots, said member having a pair of spaced openings, with said slots located in the space between said openings, and a pair of ribs secured to said element, each rib extending lengthwise along a slot near the longitudinal edge thereof more remote from the other slot, said slots and said ribs being substantially parallel to each other.

2. A buckle comprising a member having a pair of spaced slots extending through one edge thereof, a finger located between said slots and having a free end located at the mouth of said slots, a rib secured to and extending outwardly from a face of said member, said member having a recess therethrough located to one side of said slots and said rib, the closed end of one of said slots located between the planes of termini of said recess, said slots and said ribs being substantially parallel to each other.

3. A buckle comprising a member having a pair of spaced slots extending through one of the edges thereof, a finger between such slots, said member having a pair of spaced slots extending through the edge thereof opposite said first mentioned edge, said first mentioned pair of slots located in the space between said other pair of slots, and a pair of ribs secured to said element, each rib extending lengthwise along a slot of said first mentioned pair of slots and near the longitudinal edge thereof more remote from the other slot of said first mentioned pair of slots.

MARXIMILIAN C. BECKER.
